Primary Examiner — W. A. Teddy Falloway

Assistant Examiner — Yuan Yuan

(57) **CLAIM**

The ornamental design for a puzzle board as shown and described.

DESCRIPTION

FIG. 1 is a front, right and top perspective view of a puzzle board showing my new design;

FIG. 2 is a rear, left and bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof;

FIG. 9 is an enlarged view of a portion labeled as "9" on FIG. 1;

FIG. 10 is an enlarged view of a portion labeled as "10" on FIG. 2;

FIG. 11 is an enlarged view of a portion labeled as "11" on FIG. 2;

FIG. 12 is another front, right and top perspective view, showing the puzzle board wings in a folded configuration; and,

FIG. 13 is an enlarged view of a portion labeled as "13" on FIG. 12.

The long dash-short dash broken lines depict enlargement boundaries that form no part of the claim. The evenly broken lines illustrate portions of the puzzle board that form no part of the claimed design.

1 Claim, 13 Drawing Sheets
